US00D937667S

(12) **United States Design Patent** (10) Patent No.: **US D937,667 S**
 Lima et al. (45) Date of Patent: ** Dec. 7, 2021

(54) **CONNECTOR**

(71) Applicant: **REV ROBOTICS LLC**, Carrollton, TX (US)

(72) Inventors: **Francisco Musiol Lima**, Carrollton, TX (US); **Gregory Elliott Needel**, Carrollton, TX (US); **David Aaron Yanoshak**, Carrollton, TX (US); **Jonathan James Bryant**, Carrollton, TX (US); **Michael Andrew Kaurich**, Carrollton, TX (US)

(73) Assignee: **REV ROBOTICS LLC**, Carrollton, TX (US)

(**) Term: **15 Years**

(21) Appl. No.: **29/702,163**

(22) Filed: **Aug. 16, 2019**

(51) LOC (13) Cl. **08-05**

(52) U.S. Cl.

(57) **CLAIM**

The ornamental design for a connector, as shown and described.

DESCRIPTION

FIG. 1 is a perspective view taken from the front, the top and the right of a connector.

FIG. 2 is a front view of the connector, the rear view being a mirror image.

FIG. 3 is a right side view of the connector, the left side view being a mirror image.

FIG. 4 is a top view of the connector; and,

FIG. 5 is a bottom view of the connector.

1 Claim, 3 Drawing Sheets
